FIG. 8

UNITED STATES PATENT OFFICE.

HARRY ZIMMERMAN, OF FREMONT, OHIO, ASSIGNOR TO THE FREMONT MITTEN AND GLOVE COMPANY, OF FREMONT, OHIO, A CORPORATION OF OHIO.

MATERIAL-HANDLING MECHANISM.

973,331.

Specification of Letters Patent.

Patented Oct. 18, 1910.

Application filed March 10, 1909. Serial No. 482,584.

To all whom it may concern:

Be it known that I, HARRY ZIMMERMAN, a citizen of the United States, residing at Fremont, Sandusky county, Ohio, have invented new and useful Material-Handling Mechanism, of which the following is a specification.

This invention relates to the handling of material.

10 This invention has utility when embodied in a measuring-cutting-counting machine, being especially adapted for use in connection with material put up in bolts, spools or rolls, and satisfactorily handling the material even though the material is easily stretched or distorted, as knit tubular stock. The material can be handled for cutting and the mechanism effective not only in measuring off constant lengths to be cut, but also in 15 measuring off constant predetermined numbers of the cut portions.

Referring to the drawings: Figure 1 is a side elevation, with parts broken away of an embodiment of the invention in a material handling mechanism; Fig. 2 is a detail view in elevation of a portion of the pay out device and supply carrier support; Fig. 3 is an elevation, with parts broken away of the supply carrier sleeve and one 20 disk; Fig. 4 is a similar view of the second disk of the supply carrier, which with the showing of Fig. 3 completes the supply carrier reel; Fig. 5 is a fragmentary elevation of the tension device and stop motion trip features; Fig. 6 is a perspective view showing a portion of the feed device, reverse travel lock and material holding device; Fig. 7 is a fragmentary showing in elevation from the opposite side of the mechanism 25 from the view of Fig. 1; and Fig. 8 is an elevation with parts removed and broken away and looking from the right of Fig. 1.

The mechanism is mounted on the base 1, carrying the bracket or support 2 for the supply carrier and portion of pay out device. In the bracket 2 is mounted the spindle 3 over which may slip the sleeve 4 fixed to one of the disks 5 of the supply carrier. The spindle 3 has a groove 6 therein, while 30 sleeve 4 has an opposing groove 7, so that when sleeve 4 is pressed over spindle 3, the spring ring 8 will lock the sleeve and spindle together but permit of free rotation of the sleeve. The sleeve is provided with a plu-

rality of grooves 9 into any one of which 55 may lock the pair of spring thrown levers 10 to hold the second disk 5 in such relation to the first disk 5 as the roll of material permits. The outwardly extending lugs 11 allow of ready removal of this second disk 5 at any time it is desired to recharge the carrier. With a plurality of reels or supply carriers at hand, a more rapid operation may result by complete removal of the reel from spindle 3 and replacement by another 60 65 reel already charged.

The material 12, in passing from the carrier, travels over a feed device or roller 13 of the pay out device, which roller is mounted on the reciprocable arm 14 having pivotal connection 15 with the bracket 2. This arm 14 has slot 16 with which rod 17 may be locked to give roller 13 such reciprocation by the travel of rod 17 as to pay out the material as desired. The rod 17 is actuated by eccentric 70 75 18 (Fig. 7) on shaft 19, which shaft 19 is driven through worm wheel 20, from worm 21, having fast therewith the pulley 22, connected by belt 23 to pulley 24 on the countershaft 25 in bracket 26 on the base 1. 80 On this shaft 25 is the fast or fixed pulley 27 adjacent the loose pulley 28 driven by the continuous driving belt 29.

The material 12, paid out by the reciprocation of arm 14, passes from roller 13 over 85 rollers 30 and 31, being affected therebetween by the pivoted tension device 32 having thereon the adjustable weight 33, so that there is a constant drag on the material 12 in passing from roller 31, placing the material under uniform tension, to insure evenness in length of the cuttings as well as give the material more of a firmness in feeding, instead of leaving it flimsy. These rollers 30, 31 and tension device 32 are mounted in 90 95 the bracket 34 carried by the base or support 1.

The material passing from the roller 31 goes under the reverse travel lock 35 (Fig. 6), which is a pivotally mounted member 100 having its teeth directed along the line of travel of the material, so that action of the tension device 32 or of the pay out device will at once work on the reel or supply carrier for the teeth will immediately engage 105 to hold the material 12 as backward or reverse travel commences. The lock 35 is provided with the cam face 36 which is engaged

2
by the spring 37 to yieldably hold the lock in engagement with the material.

Mounted on the shaft 38 at the top of the support 1 is the arm 39 normally held down by the spring 40 so that its double row of holding teeth 41 may firmly engage the material which has passed the reverse travel lock 35. The material 12 in traveling from lock 35 and under holding device 41 moves along the way 42 which has its terminus for discharge over the receiver 43 into which the cut portions of the material are counted by the mechanism.

The feeding of the material passing the reverse travel lock 35 is brought about by the roughed segment 44 of the feed device, which by continuous rotation produces an intermittent feeding of the material under the holding device 41.

20 Fast with shaft 38 is arm 45 having roller 46 traveling on cam 47 mounted on shaft 19, so that the holding device 41 is released to permit the feed device 44 to be effective, and as soon as the feeding operation stops, 25 the cam 47 permits the spring 40 to reset the holding device 41, while the rotary cutter 48 is reciprocated between the portions of the holding device to sever a measured length of the material 12.

30 The reciprocation of cutter 48 is effected by a rocking of the arm 49 carrying the cutter (Figs. 7 and 8). This rocking of arm 49 is through the link 50 connected to arm 51 of a rock shaft having oppositely 35 extending arm 52 with roller 53 engaging the cam 54 on the side of cam disk 47.

Fixed with the rotary cutter or knife 48 is the pulley 55 (Figs. 1 and 8) connected by cross belt 56 with the pulley 57 fixed on 40 shaft 25, so that in the running of the mechanism the cutter 48 is constantly rotating.

To hold the cutter 48 normally out of the line of travel of the material 12 along the way 42, the spring 58 is provided, the action 45 of which is overcome by the cam 54. In order to avoid concussion due to the quick action of the spring 58 when running the mechanism at a high rate of speed, there is provided the buffer plunger 59 with which 50 the arm 49 of the cutter may come in contact and have its throw yieldingly taken care of.

Eccentrically mounted on shaft 19 is the pawl 60 (Fig. 7) normally held in position by the spring 61, while the dog 62 with the 55 pawl 60 contacts the ratchet wheel 63. By this device there is a counting action, each rotation of shaft 19 feeds forward a length of the material to be cut, while simultaneously there is a paying out of material 60 through action of rod 17, and further a rotation by one tooth of ratchet wheel 63 on its shaft 64. Mounted on this ratchet wheel 63 is the cam 65 contacted by roller 66 on rock arm 67 of rock shaft 68 (Fig. 8). This 65 shaft 68 has an arm 69 (Fig. 1) connected to

spring 70, so that roller 66 is normally held against the cam 65. The shaft 68 also has the arm 71 connected by link 72 to arm 73 of rock shaft 74. This rock shaft 74 has an arm 75 connected by link 76 with a rock 70 shaft 77. An additional arm 78 on rock shaft 74 is connected by link 79 to cranked rock shaft 80, while a fourth arm 81 on rock shaft 74 is connected by link 82 with the cranked rock shaft 83. Connected to be 75 rocked with the cranked shafts 77 and 83 are the receiver bottom sections 84, while connected to be rocked with the cranked shafts 74 and 80 are the receiver bottom sections 85. While the receiver 43 is not shown 80 in Fig. 8, the bottoms 84 are shown as closed and the bottoms 85 as open. In Fig. 1 the relation of the bottoms is shown reversed, 84 open and 85 closed.

The material 12 in passing from roller 31 85 to lock device 35 passes under the weighted arm 86 of the stop motion (Figs. 1 and 5). This arm 86 has an angular extension 87 pivoted on the frame 88, so that as the material supply fails and the weight 86 falls, 90 it will cause the wing 89 on the extension 87 to move into the line of travel of the enlargement 90 carried by reciprocable rod 17. The frame 88 is carried by the movable bar 91 which has a fork or pair of fingers 92 95 between which the material 12 passes to properly locate the weighted arm as to the material. Obstructions in material engage fingers 92 to operate the stop motion. The remote portion of the movable bar 91 is 100 slidable in the way 93 carried by the receiver 43. This bar 91 is connected to hand lever 94 pivoted at 95 to the receiver supporting frame. The hand lever 94 has a belt shifting fork 96 to engage the continuously driving belt 29, so that when enlargement 90 on the rod 17 is effective to move the bar 91 the belt 29 is shifted from the fast pulley 27 to the loose pulley 28 and the mechanism is stopped.

110 In regular operation the mechanism needs no further attention than keeping the supply carrier charged and removing the counted quantities of cut material.

Starting up the charged mechanism, with 115 the material 12 led therethrough as indicated, cutter 48 is rotating and shaft 19 is driving the variously interconnected devices which so mutually coact in performing their cycles of operation which lead up to the 120 unitary result that the timing of the intermittent actions brings about a continuity and regularity combined with great speed which means a considerable saving in labor as well as accuracy as to result attained. 125 Shaft 19, through the pay out arm 14 to which it is connected by eccentric 18 and rod 17 withdraws material from the carrier reel sleeve 4, which the feed device 44 carries forward under the holding device 130

41 for the cutter 48 to act upon in measured lengths of no variation, for the tension device 32 places a constant drag on the material, while lock 35 prevents backward travel. The cut length of material in being pushed by the holder 41 with the next length of material to be cut, is deflected toward the receiver 43 by the pivoted hood 97, mounted above the way 42. This shoving of the material 12 forward occurs after knife 48 is removed from the line of way 42. Coincident with the travel of the cutter 48 through the material and back out of the way, there is the operation of the pay out device, the feeding of the next length of material to be cut, the release and setting of the material holding device, the counting up of the cuts made, and after a predetermined number of cuts are made, the dumping of the receiver 43 by opening of bottoms 85 and closing of bottoms 84, a little later followed by bottoms 84 dumping upon bottoms 85 for a subsequent repetition of the operation.

25 Cam 47, Fig. 7, through crank 45 lifts holder 41 to permit the next length of material to be fed by segment 44. As the feeding action ceases, holder 41 at once engages the material by force of spring 40 as cam 47 again presents smaller radius to cam roller 46. While roller 46 is traveling over this smaller radius of cam 47, the cam 54 (Figs. 7, 8) through rock arms 52, 51 and link 50, oscillates link 49 carrying the rotary cutter 48, across the held material to sever the measured length thereof. As soon as roller 53 passes over cam 54, spring 58 retracts the cutter to permit the succeeding length of material to be fed as the enlarged portion of cam 47 lifts the holder 41.

Each rotation of shaft 19, besides causing the feeding and cutting of a length of material, actuates the pay out device, and further counts one tooth on the wheel 63.

45 Each rotation of the counter wheel 63 effects a dumping from the receiver of a predetermined quantity of cut material. This dumping of the predetermined number of cuttings is effected by cam 65, rock crank 67, rock shaft 68, arm 71 and link 72. While roller 66 is traveling on the larger radius portion of cam 65, the bottom sections 85 of receiver 43 are in holding position and sections 84 are in open position. When the roller 66 reaches the smaller radius of cam 65, to which cam it is held by spring 70 (Fig. 1) engaging arm 69 of rock shaft 68, the movement of link 72 resulting from this rocking of shaft 68, causes links 76 and 82 to close the bottom sections 84 and dump or open the bottom sections 85 to discharge a predetermined number of cut portions of material. The bottom sections 84 catch the cuttings from operation while this discharge is taking place. The continued operation

causes roller 66 to again reach larger radius portion of cam 65, when bottom sections 85 are closed and sections 84 opened, the latter discharging upon the former. The continued rotation of cam 65 causes repetitions 70 of this counting operation. As before recited, an exhausting of the supply of material, will at once result in the dropping of arm 86 and stopping of the mechanism by shifting the belt 29.

The working in together of the parts as disclosed has produced a mechanism of maximum effectiveness and minimum of parts for carrying out a complex operation involving many details.

What is claimed and it is desired to secure by Letters Patent is:

1. A material handling mechanism embodying a supply carrier, a pay out device therefrom, a tension regulator, a reverse 85 travel lock, a feed device, a cutter, a material holder for the cutter, a receiver for the cut material, and a counting device for dumping the receiver.

2. A material handling mechanism embodying a rotary intermittently effective feed device, there being a fixed bearing for the device limiting its movement to rotation, a holder locking the material during the intermissions of the feeding, and a cutter for severing the material while held by the holder.

3. A material handling mechanism embodying a freely movable supply carrier, a cutter for acting upon the material supplied from the carrier, and a pay out device intermittently removing material from the carrier for the cutter.

4. A material handling mechanism embodying a reciprocable pay out device and a 105 tension device regulating the feeding of the material paid out.

5. A material handling mechanism embodying a way for receiving material to be severed, an intermittent feed device effecting travel of material along the way, a holding element for the material during the intermissions of the feeding, and a rotary cutter reciprocable to sever the held material.

6. A material handling mechanism embodying a supply carrier, a pay out device for removing material from the carrier, a cutter for acting upon material from the pay out device, a counter for the number of portions of the material cut, and a receiver 115 for the cut portions of material, from which receiver the counter is effective to discharge a predetermined number of cut portions of the material.

7. A measuring material cutter, a driver therefor, and a stop motion coacting with the material to disconnect the driver from the cutter.

8. A material handling mechanism embodying a shaft, an intermittent feed device 130

- thereon, and a reciprocable pay out device actuated from the shaft to supply material to the feed device.
9. A material handling mechanism embodying a shaft, an intermittent feed device thereon comprising a material engaging segment, and a material release actuated from the shaft to permit feeding of the material by the device.
10. A material handling mechanism embodying a shaft, an intermittent feed device thereon comprising a material engaging segment, and a cutter connected to be reciprocated by the shaft.
11. A material handling mechanism embodying an intermittent pay out device, and a tension device for maintaining taut the material paid out, said tension device including a pivoted member to rest upon the material and an adjustable weight carried thereby.
12. A material handling mechanism embodying a pay out device having a reciprocable element, a stop motion having a drop arm held by the material, and connections permitting the reciprocating element to actuate the arm and stop the mechanism when the material supply fails.
13. A material handling mechanism embodying a bracket, a removable supply carrier reel mounted upon the bracket and having a sleeve, a disk fixed to the sleeve and a second disk adjustable thereon.
14. A material handling mechanism embodying a pay out device, and a reverse travel lock coacting with the material to insure regular action of the pay out device.
15. A material handling mechanism embodying a receiver having a plurality of superposed bottoms, and a counting device for controlling the receiver bottoms to discharge material from one portion of the receiver to another.
16. A material handling mechanism embodying a pay out device, a feed device intermittently operable to move the material paid out, a holding device released during the feeding operation, and a cutter for the material operable during the feed intermission.

In testimony whereof I hereunto set my hand in the presence of two witnesses.

HARRY ZIMMERMAN.
